UNITED STATES PATENT OFFICE.

ISAAC GUSTAVE MARKS, OF NEW ORLEANS, LOUISIANA.

AUTOMATIC CLOSURE FOR GARBAGE-CANS.

1,143,847.

Specification of Letters Patent. Patented June 22, 1915.

Application filed September 22, 1914. Serial No. 862,951.

To all whom it may concern:

Be it known that I, ISAAC GUSTAVE MARKS, a citizen of the United States, residing at New Orleans, in the parish of Orleans and State of Louisiana, have invented certain new and useful Improvements in Automatic Closures for Garbage-Cans; and I do hereby declare the following to be a full, clear, and exact description of the invention, such as will enable others skilled in the art to which it appertains to make and use the same.

This invention relates to garbage cans and has for its object to provide an automatic closure for said cans, which will be more efficient in action, simpler in construction and less expensive to manufacture than those heretofore proposed.

With these and other objects in view, the invention consists in the novel details of construction and combinations of parts more fully hereinafter disclosed and particularly pointed out in the claims.

Referring to the accompanying drawings, forming a part of this specification in which like numerals designate like parts in all the views:—Figure 1 is an elevational view partly in section of a garbage can and closure made in accordance with my invention; Fig. 2 is an elevational view of the parts shown in Fig. 1, but looking in the direction at right angles to that in which Fig. 1 is seen; Fig. 3 is a view similar to Fig. 1, but showing the closure removed from the can and ready to be automatically replaced thereon; and Fig. 4 is a sectional view taken on the line 4—4 of Fig. 2, looking in the direction of the arrows.

1 indicates the body of the can which may be of any suitable dimensions and construction, 2 a cover therefor, preferably provided with the flared extension 3, and handle 4, while 5 indicates a pair of pivoted supports for said cover pivoted as at 6 to the body 1 of the can, and provided with the slots 7, through which pass the pins 8, or other connections to the cover. The said supports 5 are each provided with downwardly projecting extensions 10 to which is secured as at 11 the weighted member 12, adapted to partially encircle the can, and the weight 13 thereof adapted to project up over the top edge thereof when the cover is removed as will be clear from Fig. 3.

It will be observed that the weight 13 being pivoted at 6, and the parts being dimensioned approximately as illustrated, the

cover will not permit the weight to occupy a position vertically over the pivots 6, so that said weight in all positions exerts a tendency to move the cover toward the right as seen in Fig. 3, but when it has reached the position shown in Fig. 1, any further downward movement of the weight will cause it to either strike the support on which the cover rests, or else to strike the lower edge of the can; in either of which cases its further downward movement will be arrested and the flaring extension 3 of the can will prevent the can from being uncovered.

The operation of my invention will be clear from the foregoing, but may be briefly summarized as follows:—When it is desired to open the can the operator grasps the handle 4 and lifts the cover 2 vertically, which causes the pins 8 to move from near the bottoms of the slots 7 to near the tops thereof and enables the vertical flange portion 15 of the cover to disengage the vertical wall of the can and thereby to become unlocked, so to speak, from said vertical wall, as will be clear from the full and dotted line positions shown in Fig. 1. The cover having been thus raised to its dotted line position indicated, the operator next moves the same toward the left, as shown in Fig. 1 and to the full line position as seen in Fig. 3, whereupon the weight 13 is lifted from the position shown in Fig. 1 to the position shown in Fig. 3, and acts at the end of the levers formed by the extensions 10 to automatically return said cover to its closing position. During the return movement, the flared extension 3 assists in seating the cover on the can and causing the vertical flange portion 15 to surround the wall of the can, while gravity causes the pins to resume their former position near the bottoms of the slots 7.

It will thus be seen that it is practically impossible to leave this garbage can uncovered unless the cover 2 is intentionally prevented from returning to its closed position. When such is the intention however, said cover is easily locked in its full line position shown in Fig. 3, by simply placing a support or stick or other article under the weight 13, or between said weight and the top rim of the can body 1, or otherwise supporting said weight.

It is obvious that those skilled in the art may vary the details of construction as well as the arrangement of parts without depart-

ing from the spirit of my invention and therefore I do not wish to be limited to the above disclosure except as may be required by the claims.

5. What I claim is:—

1. In a garbage can the combination of a closure; a pair of pivoted supports provided with slots for said closure; connections carried by said closure adapted to traverse said 10 slots; and a counter weight connected to said supports adapted to automatically return said closure when removed from its closing position, substantially as described.

2. In a garbage can the combination of a 15 closure provided with a flared extension; a pivoted support for said closure provided with a slot and pin connection; and a counter weight for automatically returning said closure when displaced rigid with said 20 support, the parts being so dimensioned that said weight is adapted to be raised to near the top edge of the can when the cover is moved to its extreme open position and to be lowered to near the bottom edge of the 25 can when the cover is in its closed position, substantially as described.

3. In a garbage can the combination of a cover having a vertical member adapted to surround the top portion of the wall of the can and having a flared member extending 30 outwardly from said vertical member; a pair of pivoted supporting members for said cover, having slots; pins carried by said cover entering said slots and adapted to traverse said slots when the cover is raised and lowered; an extension rigid with one of said pivoted supports; and a weighted member rigid with said last named extension, the parts being so arranged that said cover may be vertically lifted to disengage 35 said vertical member from the top edge of the can, and then turned to one side to lift said weight, while the parts are so dimensioned that said weight will in all positions tend to return said cover to its closing position, substantially as described.

In testimony whereof I affix my signature, in presence of two witnesses.

ISAAC GUSTAVE MARKS.
